(57) **CLAIM**

The ornamental design for a headlight for motorcycles, as shown and described.

DESCRIPTION

FIG. 1 is a first perspective view of a headlight for motorcycles showing my new design;

FIG. 2 is a second perspective view thereof;

FIG. 3 is a front view thereof;

FIG. 4 is a back view thereof;

FIG. 5 is a left side view thereof;

FIG. 6 is a right side view thereof;

FIG. 7 is a top view thereof;

FIG. 8 is a bottom view thereof; and,

FIG. 9 is an enlarged view of the selected portion in FIG. 2. The broken lines shown in the drawings depict portions of the headlight for motorcycles that form no part of the claimed design.

The long dash broken lines shown in the drawing of FIG. 9 depict the boundaries of the enlarged view and form no part of the claimed design.

1 Claim, 9 Drawing Sheets
